(57) **CLAIM**

The ornamental design for a pet water fountain, as shown and described.

DESCRIPTION

FIG. 1 is a top front right perspective view of a pet water fountain.

FIG. 2 bottom rear left perspective view thereof.

FIG. 3 is top plan view thereof.

FIG. 4 is a left-side elevation view of the pet water fountain, the right-side elevation view being a mirror image thereof.

FIG. 5 is a bottom plan view thereof.

FIG. 6 is a rear elevation view thereof; and,

FIG. 7 is a front elevation view thereof.

The broken lines depict unclaimed features of the pet water fountain, for illustrative purposes only and form no part of the claim.

1 Claim, 7 Drawing Sheets
